UNITED STATES PATENT OFFICE.

AUGUST W. VOLLSTORF, OF TOLEDO, OHIO.

DESIGN FOR A FAN.

SPECIFICATION forming part of Design No. 23,549, dated August 7, 1894.

Application filed April 12, 1894. Serial No. 507,316. Term of patent 7 years.

To all whom it may concern:

Be it known that I, AUGUST W. VOLLSTORF, a citizen of the United States, residing at Toledo, county of Lucas, and State of Ohio, have 5 invented and produced a new and original

Design for Fans, of which the following is a specification, reference being had to the accompanying drawing, showing a part thereof.

The figure is a plan view of a fan showing 10 my design.

The leading features of my design consist in a fan provided with a series of portraits or faces radiating from a central body and having a concentric circle intersecting each portrait as shown. 15

1 designates the fan as shown, heartshaped, having a series of portraits or faces 2, radiating from a central body and having a concentric circle 3 intersecting each portrait as shown. 20

What I claim is—

The design for a fan, substantially as shown and described.

In testimony that I claim the foregoing as my own I hereby affix my signature in presence of two witnesses. 25

AUGUST W. VOLLSTORF.
